UNITED STATES PATENT OFFICE.

JEROME B. STAADEKER, OF LOUISVILLE, KENTUCKY.

SUIT-HANGER.

1,130,643.

Specification of Letters Patent.

Patented Mar. 2, 1915.

Application filed September 4, 1912. Serial No. 718,499.

To all whom it may concern:

Be it known that I, JEROME B. STAADEKER, a citizen of the United States, residing at Louisville, in the county of Jefferson and 5 State of Kentucky, have invented new and useful Improvements in Suit-Hangers, of which the following is a specification.

This invention relates to suit hangers and packing forms, the object in view being to 10 provide a simple, cheap, and effective device of the class described which, when not in a hanging position, is adapted to be placed together with a number of other suit hangers of similar construction, in the tray or 15 body of an ordinary trunk, the frame of the device being such that the hanger will fit snugly within the tray or body of the trunk, being incapable of moving about therein during transportation.

20 A further object of the invention is to provide a suit hanger which is perfectly flat, so that any number of hangers may be placed one upon the other, either with or without a pair of trousers applied thereto.

25 The hanger also embodies a foldable suspending hook which is adapted to be held within the outer confines of the hanger, so as not to interfere with placing the same within the tray of a trunk or removing the same 30 therefrom.

With the above and other objects in view, the invention consists in the construction, combination and arrangement of parts, as will be hereinafter more fully described, 35 illustrated in the accompanying drawings, and pointed out in the claim hereunto appended.

In the drawings: Figure 1 is a plan view 40 of a suit hanger, showing a pair of trousers held thereby. Fig. 2 is a longitudinal section on the line 2—2 of Fig. 1. Fig. 3 is a cross section on the line 3—3 of Fig. 1.

The suit hanger contemplated in this invention comprises a flat frame which may 45 be constructed of any suitable material, such as wood or metal. This frame comprises the oppositely located substantially parallel side bars 1 and 2, and the end cross bars 3 and 4, which, it will be noted, extend at 50 their extremities beyond the outer edges of

the side bars 1 and 2, so as to adapt the frame as a whole to fit snugly in a trunk tray or in the body of the trunk itself, the bars 3 and 4 being made of a length equal to the internal width of the tray or trunk, 55 while the length of the bars 1 and 2 is equal to the internal length of the trunk. The end cross bar 3 forms a coat hanger, when the device as a whole is suspended.

In addition to the side and end bars, hereinabove described, suitable cross braces 5 and 6 may be employed to give additional strength to the frame, said cross braces lying in the same common plane with the side and end bars.

At or near one end of the frame, there is arranged an intermediate cross bar 7, and lying in parallel relation and close proximity to the intermediate cross bar 7 is a clamping bar 8, one end of which is fixedly 70 secured to the frame, at 9, while the other end is adapted to have a clamping loop 10 slipped over the same, said clamping loop also embracing the intermediate cross bar 7.

The trousers are placed between the bars 7 and 8, and clamped by the loop 10. Connected to the center of the top end bar 3 is a suspending hook 11, having a long shank 12, terminating at its lower end in a shoulder 13 which prevents the hook from escaping 80 in an upward direction. The top edge of the bar is recessed, as shown at 14, to form a socket, into which the hook proper may be drawn by sliding the shank downwardly. This houses the suspending hook entirely 85 within the outer confines of the frame, so that it will not interfere with the placing of the trousers stretcher in a tray or trunk.

When hanging up the top cross bar 3 is 90 designed to support a coat in addition to the trousers which are supported by the cross bar 7.

What is claimed is:—

A garment hanger comprising a flat rigid frame having an intermediate trousers supporting portion, a pair of end bars of the same relative length, the said bars having their ends extended beyond the sides of the frame, and a rigid curved coat supporting bar extended at its ends into the sides of 100

the frame and also extended directly into the adjacent end bar, the extension of the said end bars beyond the sides of the frame being adapted to permit the sides of the coat to be arranged wholly within the plane of the ends of said bars when the coat is in position upon the frame.

In testimony whereof I affix my signature in presence of two witnesses.

JEROME B. STAADEKER.
